UNITED STATES PATENT OFFICE

JEAN DELATTRE-SEGUY, OF CHICAGO, ILLINOIS, ASSIGNOR TO UNIVERSAL OIL PRODUCTS COMPANY, OF CHICAGO, ILLINOIS, A CORPORATION OF SOUTH DAKOTA.

PROCESS OF CRACKING OIL

Application filed June 28, 1926. Serial No. 118,979.

This invention relates to improvements in process of cracking oil, and refers more particularly to the cracking of petroleum oil to produce therefrom lighter hydrocarbons which crude petroleum or topped crude contains more or less objectionable extraneous matter such as salt, saline compounds, earthy materials or the like.

It has been found in practice that in cracking crude petroleums of this character in the type of cracking plant now used, in which the oil is passed through a cracking coil mounted in a furnace, that there is a tendency for the salt to deposit out and clog or choke up the tubes.

The object of the present invention is to remove the salt or like compounds from the petroleum before they reach the primary cracking coil as part of a continuous process.

In the drawing, the single figure shows a somewhat diagrammatic view of an apparatus suitable for carrying out the present invention.

Referring to the drawings, 1 designates a bottom fired furnace as shown. In the coolest part of the furnace is mounted the primary cracking coil 2, while in the hottest part of the furnace is mounted the cracking secondary coil 3. The coil 2 connects by transfer line 4 having throttle valve 5 to an enlarged expansion chamber 6 preferably located outside of the fire zone. The expansion chamber 6 may be provided with the residue drawoff lines 7 controlled by the valves 8, manholes 9 and the vapor outlet pipe 10 controlled by the valve 11. This pipe 10 leads to the side of a dephlegmator 12, which dephlegmator is provided with the reflux drawoff pipe 13 connected to pump 14, and thence by pipe 15 to the inlet of the coil 2. The top of the dephlegmator is provided with vapor outlet pipe 16 having throttle valve 17 leading to water condenser pipe 18, thence to the receiver 19. The receiver 19 may be provided with gas outlet pipe 20 controlled by the valve 21 and liquid drawoff pipe 22 controlled by the valve 23. The dephlegmator 12, may be cooled by liquid drawn off from

the receiver 19 through the pipe 24 and pump

25 or by any other suitable cooling means, not shown.

The crude petroleum or topped crude containing the extraneous constituents referred to, is fed from any suitable source of supply 55 to the heating coil 3 by means of the feed line 26 and pump 27. The oil passes from the coil 3 through the transfer line 28 having throttle valve 29 to the lower side of the expansion chamber 6, as shown. A pump 30 60 may be interposed in the line 28.

In carrying out the process, the coils and more or less of the expansion chamber are filled with oil, and raised to initial conditions of heat and pressure. The petroleum containing the objectionable extraneous matter is then fed into the coil 3 where it is heated under substantially atmospheric pressure to a transfer temperature of say 950° F. more or less, at which temperature it enters the expansion chamber 6. The oil in the primary heating coil 2 is heated to a transfer temperature of say 850° F., and the primary heating coil 2, expansion chamber and dephlegmator maintained under a substantially uniform pressure of say 150 pounds. In order therefore, to get the oil from the coil 3 into the expansion chamber, it will be necessary to use the pump 30 to force the oil into the expansion chamber against the operating 70 pressure contained therein.

As the oil from the coil 3 enters the expansion chamber, it will be more or less completely vaporized, and the salt or other extraneous matter deposited out and drawn out with the 85 residue and coke. The vapors from the oil in the coil 3, as well as the vapors from the oil in the coil 2 will pass out of the expansion chamber into the dephlegmator where the insufficiently cracked portions will be condensed and returned through lines 13 and 15, and pump 14 to the inlet of the primary coil 2.

The coil 3 is preferably of smaller diameter and shorter length than the coil 2, and the 95 velocity of the oil is such as to more readily sweep out of the coil the salt or the like, into the expansion chamber 6 than would be the case where it passed through the larger and longer cracking coil 2.

I claim as my invention:

1. A process for cracking hydrocarbon oil containing salt and other deleterious solid constituents comprising maintaining a bulk supply of oil constituents in an enlarged reaction zone, taking off vapors from said reaction zone, subjecting such vapors to reflux condensation, delivering hydrocarbon oil constituents containing salt or other deleterious compounds to a heating coil wherein such hydrocarbon oil is subjected to a high temperature while under a relatively low pressure, increasing the pressure on said hydrocarbon oil and delivering the same to said enlarged reaction zone wherein the salt and solid constituents separate from the oil, continuously passing reflux condensate separated from the vapors subjected to reflux condensation through an independent heating coil wherein it is subjected to a cracking temperature while maintained under a super-atmospheric pressure, delivering the heated reflux condensate to said enlarged reaction zone and maintaining said enlarged reaction zone under substantially the same pressure as that maintained on the reflux condensate passing through said independent heating coil.
2. A process for cracking hydrocarbon oil containing deleterious solid constituents comprising maintaining a supply of oil constituents in an enlarged zone, subjecting vapors separated in said zone to reflux condensation, initially heating the hydrocarbon oil containing deleterious solids to high temperature while under a relatively low pressure, increasing the pressure on said hydrocarbon oil, introducing the same at said elevated pressure into said zone, continuously subjecting reflux condensate separated from the vapors subjected to reflux condensation to a cracking temperature under a relatively high superatmospheric pressure, introducing the heated reflux condensate to said zone and maintaining said zone under a superatmospheric pressure substantially above the pressure maintained on the hydrocarbon oil containing the deleterious solids during the initial heat treatment thereof.

JEAN DELATTRE-SEGUY.
